[57] CLAIM

The ornamental design for a control unit for a combined automobile cassette player and radio, as shown and described.

DESCRIPTION

FIG. 1 is a front, top and left side perspective view of a control unit for a combined automobile cassette player and radio showing our new design in full lines, the broken line matter being for illustrative purposes only and forming no part of the claimed design;

FIG. 2 is a front elevational view; and

FIG. 3 is a right side elevational view.

The rear of the control unit is conventional.
